UNITED STATES PATENT OFFICE.

JAMES LOGAN FITTS, OF PENSAUKEN TOWNSHIP, CAMDEN COUNTY, NEW JERSEY,
ASSIGNOR TO WARREN WEBSTER & COMPANY, OF CAMDEN, NEW JERSEY, A COR-
PORATION OF NEW JERSEY.

THERMOSTATICALLY-CONTROLLED VALVE.

Application filed May 23, 1919. Serial No. 299,227.

To all whom it may concern:

Be it known that I, JAMES LOGAN FITTS, a citizen of the United States, residing in Pensauken Township, Camden County, New Jersey, have invented certain Improvements in Thermostatically-Controlled Valves, of which the following is a specification.

The object of my invention is to provide means for automatically controlling the admission of steam to a radiator coil or other heating or heat distributing element and thereby prevent overheating and fuel waste, and to maintain under certain conditions a more even temperature than has been possible by any form of hand-controlled devices heretofore employed.

A further object of my invention is to eliminate the need for and use of any auxiliary power such as might be supplied by compressed air or any other fluid or liquid under pressure, or electricity, for effecting such control, with the consequent absence of all pipes, wires, or other accessories necessary for use therewith.

25 A further object of my invention is to provide a device which is self-contained and of such a character that the desired adjustment can be readily effected to obtain the heating service intended.

30 And a still further object of my invention is to eliminate the placing of a thermostat on a wall, and the necessary connection therewith between the steam valve of the heating element, as well as the work necessary to install such structure.

35 With these and other objects in view, my invention relates to that type of heat controller in which the admission of steam to the individual radiating unit, coil, or other form of heat distributing element, is regulated without any other source of power than that of the heat of the steam in the supply pipes together with the heat of the atmospheric air adjacent thereto. Under such 40 conditions, the structure or apparatus forming the subject of my invention may be used on or in connection with any individual radiation unit, and without reference to or interference by or with any other radiator or steam heating unit.

50 It is well known that rooms or other spaces heated by steam, wherein the radiators are controlled by the ordinary hand manipulation of the supply valves, are fre-

quently overheated, especially in mild 55 weather; resulting in loss of fuel by furnishing unnecessary heat when weather conditions permit the windows of a room to be open, and also reducing the efficiency and producing serious injury to health of the 60 occupants of such overheated rooms. Closing of the steam valves is forgotten, and the observance of a thermometer is sometimes neglected; therefore actual overheating is not known until the overheating becomes 65 uncomfortable and greatly in excess of that considered correct and healthful. A healthful temperature, generally recognized as 68° F., should not be exceeded.

70 In certain chemical and mechanical processes it is frequently desirable to maintain a given room or other enclosed space at a fairly constant temperature, and automatic means are provided by my invention for effecting this result.

75 My invention, briefly stated, comprises a steam controlling valve, with a thermostat attached thereto and insulated from the heat of the radiator or steam pipe, the construction of which combined valve and thermostat is comparatively simple, and the whole arranged in a form suitable for connection with the steam supply pipe of a two-pipe steam heating system in which there is sufficient difference in supply and 80 return pressures to cause the steam to flow.

85 It has heretofore been customary to control the steam supply and the resulting room temperature by placing a thermostat on the wall, or on or near a door jamb, at a point 90 about 4½ to 5 feet from the floor, usually called the "breathing line." It is common knowledge that in confined spaces there is very little circulation of the air and that the higher layers or strata are warmer than those near the floor. While the heat from a steam radiator tends to rise and produce some circulation, it is not usually enough to produce an even temperature throughout the entire space. Considering therefore that there are differences of temperature in the various layers or strata of the air in a room, there is always a lower temperature nearer the floor and I have found that this lower 95 temperature bears a fairly definite relation to the "breathing line" temperature.

100 The actual difference in temperature (usually expressed in degrees F.) depends upon

other factors, such as the building structure; size and height of the room; and the outside air temperature, &c. But for each apartment the relation is practically constant; the disturbing factor being the outside air temperature which, in very cold weather is greater, and in mild weather is less. These differences in temperature between the floor and the "breathing line" are from 2° to 3° F. to 7° or 8° F., but as before stated, are fairly constant for each room; variations, usually slight, only occurring in cold or mild weather.

Under these conditions, a thermostat located either at the top of the radiator or near the floor may be set so as to maintain the desired temperature at the "breathing line"; due allowance being observed for the difference in temperature at the "breathing line" stratum with respect to the location of the thermostat, and when so set such thermostat will react in accordance with any changes in the temperature of the air at the "breathing line".

In this invention I have utilized this relative constancy to so control the steam admission that when the "breathing line" temperature is approximately 68° F. (or any other reasonable or desirable temperature) the thermostat will be affected by the temperature of air in its immediate proximity and will operate to shut off the steam supply.

These and other features of my invention are more fully set forth hereinafter, and in order to clearly understand the same, reference is made to the accompanying drawings, in which:

Figure 1, shows a perspective view of a portion of a room with an ordinary form of steam radiator therein; showing the location of the controlling valve and the thermostat with respect thereto.

Fig. 2, is a sectional elevation of the controlling valve and thermostat in their relative position with respect to each other.

Fig. 3, is a plan view of the structure shown in Fig. 2.

Fig. 4, is a front elevation of the thermostat.

Figs. 5 and 6, are sectional views illustrating modified forms of the valve and valve body, and certain of their accessories, and

Figs. 7 and 8, are, respectively, a front elevation and a sectional view of another form of a thermostatic element within the scope of my invention.

Referring to the drawings, more particularly Fig. 1, 1 is a steam radiator, with steam supply or inlet pipe 2, and condensation return or outlet pipe 3, (with which may be employed any suitable or modern form of a steam trap located therein to relieve the radiator of air and water yet

hold the steam). Connected to the steam supply or inlet pipe 2 is my improved controller valve 4, with the attached thermostat 5; the latter being shown as facing outward from the radiator. The valve 4, with its thermostat and other appurtenances may be located at the floor, for a "bottom connected" radiator, but the preferred location is at the top of a "top connected" radiator, as indicated in the drawing. Whether located at the bottom or at top of the radiator, it is affected by the temperature of the air stratum in which it is placed and by slight currents set up by a heated radiator; which temperature, while relatively lower than the air at the "breathing line", is relatively constant as before stated.

In Fig. 2, of the drawings, showing an enlarged sectional view of the steam valve 4, and thermostat 5, the shell or casing of the valve is indicated at 10, and may be provided with an inlet port 11, a port or passage 12, formed in the diaphragm or wall 13 within the valve chamber 14, and an outlet port 15 through which the steam may flow to the radiator. The inlet port 11 communicates with the steam supply pipe 2, the outlet port 15 communicates with a pipe 6 connected to the radiator, while the port 12, through which the steam entering via port 11 may find its way to port 15, is controlled by an automatically controlled valve member to vary the amount of steam passing to the radiator.

Secured to the upper part or top of the valve body, by screws or other means, is a cover 16, with a bracket portion 17, and this bracket portion may carry an insulating plate 18 to which the thermostat 5 may be attached.

Disposed within the valve chamber 14 and depending from its cover 16; being attached to the flange 19 of a screw plug 20, threaded into said cover and providing a suitable vapor-tight joint, is an expansible metal cylinder 21, preferably of bellows form, or of multiple disk type, forming a chamber 22, to which is attached a valve stem 23, to the flange 24 of which the cylinder 21 is secured, and said stem carries a valve piece 25 adapted to close the port 12. The screw plug 20 is provided with a tubular passage 26, leading to a chamber 27 within the cover 16. A gasket or other suitable form of packing is shown at 28 in order that the cover 16 may, with the securing screws 29, form a steam-tight top closure for the valve casing.

The cover 16 is preferably provided with an upwardly extending boss 30, having a tubular passageway 31 communicating with the chamber 27 and in line with the passage 26 of the screw plug 20; a screw plug closure 32 being adapted to said port or passage 31 in the boss 30 for the purpose 130

of hermetically closing the same when the structure is in operation. A guard cap 33, designed to protect said screw plug closure 32 and to be sealed against tampering, may 5 also be provided.

Communicating with the passageway 31 is a passage 35 extending through the cover 16 or a horizontal enlargement 36 of the same and the bracket part 17, and with this 10 passageway a small tube 37 is connected, which tube leads to and affords communication with the chamber of the thermostat 5.

Within the chamber 22 of the expandible metal cylinder 21, I preferably place a stop 15 designed to limit the contraction of said chamber to definite dimensions, and for this purpose I have shown a tubular member 38, which may have notches 38^a at the upper and lower ends, so that any fluid within said 20 chamber may communicate freely with the interior of said tubular member 38. I have shown half round notches, but they may be of any other suitable shape and perform the function desired.

25 Within the chamber 22 of the expandible metal cylinder 21, I may also place a suitable filling substance 39, which may be of wax, such as paraffin, which is solid at ordinary or maximum atmospheric temperatures 30 but which at the temperature of steam is a fluid, and for illustrative purposes this may be in amount such as to partially fill said chamber 22 to the dotted line α . The filling material is not necessarily in fixed 35 volume, but may just fill the chamber, or partially fill the same, or in some instances it may be omitted altogether. A heavy, chemically inert oil, might be used, but a material solid at ordinary temperatures is to 40 be preferred, for when cold or relatively so, it is fixed and forms a solid internal support, protecting the corrugated metal casting, and it remains in place. Its use will be described later.

45 Referring to Fig. 2, the thermostatic element 5 may include or comprise a corrugated of accordion-jointed cylinder 40, with an upper head 41 and a lower head 42; such cylinder forming a chamber 43 adapted to 50 be filled with liquid. This chamber is supported between rigidly mounted brackets 44 and 45 carried by a backing plate 46; the upper bracket being threaded for an adjusting screw 47 adapted to engage a recess 48 in the upper head 41, and such screw provides for changes in the length of the cylinder 40 under the varying operating conditions. The lower head 42 of the cylinder 40 is detachably mounted in the lower 55 bracket and is preferably so connected therewith as to be fixed against rotative movement. In the present instance, such lower head is shown as provided with a squared boss 49 adapted to enter and fit a squared 60 hole or recess 50 in the lower bracket, but

any other suitable means may be employed that will prevent rotation of the cylinder 40 when the screw 47 is turned in either direction. The cylinder 40 provides that the chamber 43 may elongate under internal pressure due to expansion of the fluid contained therein when such fluid is heated, and it may be compressed lengthwise by turning said screw against the same; movement of the screw with respect thereto being necessary in calibrating the device to operate at the desired and predetermined temperature. When once set, the cylinder is held in a fixed position between the 70 brackets 44 and 45.

75 The end of the tube 37 is preferably attached to the lower head 42 at the center of the squared boss 49, so that the interior of the chamber 43 is in direct communication with the interior of the chamber 22 within the valve casing.

80 The base 46 is preferably attached to an insulating plate 51, and may be enclosed by a protective cover 52 of thin metal, having slots or perforations 53 to permit free 85 access and circulation of air around the cylinder 40 forming the chamber 43, which cylinder, being corrugated, presents a greatly enlarged surface to be affected by the 90 temperature of the atmosphere.

95 The insulating plate 51 of the thermostat may be secured by a metal band 54, preferably perforated at 55, to the insulating plate 18 connected to the top closure 16 of the valve 4, so that the latter, with the thermostat, is substantially a unitary structure.

100 Attached to the adjusting screw 47 is a circular dial 56 with scaled divisions representing degrees of temperature F., which, in relation to a fixed pointer 57, attached to 105 the upper bracket 44, indicate the true temperature at which the device is calibrated to operate.

110 The tube 37 which leads from the cover 16 of the valve 4 to the thermostat, is preferably suspended between said plates 18 and 51 in the form of a coil, or with horizontal return bends 58, and its office is that of a condenser; such portion of the tube being cooled 115 by the air circulating between said insulating plates through the holes or perforations 55 in the supporting band 54. By this arrangement, any liquid contained within said tube 37 will gravitate to the lower part of 120 said condensing portion 58, next to the thermostat, while the vapor of such liquid will occupy the upper portion thereof and the chamber 22, or such portion thereof unoccupied by the filling material 39.

125 It will be understood, of course, that the thermostat chamber 43; the connections with the heads 41 and 42 and with the tube 37 and its condensing portion 58, and the connection with the cover 16 communicating 130 with the chamber 22 within the valve body,

are all liquid and vapor tight, so that part of the structure providing for circulation between the chamber 22 and the thermostat chamber 43, including the metal walls of the several chambers, is hermetically sealed.

The valve structure shown in Fig. 2, is illustrated as having a tubular thimble or sleeve 60 providing the port 12 and a seat for the valve 25 designed to close the same; such thimble having a forced fit. In Fig. 5, I have shown a similar sleeve or thimble, with a conical valve 25^a. In this arrangement the steam supply pipe 2 is shown at the side of the valve casing communicating with a port 11^a.

In Fig. 6, I have shown another form of valve 25^b, having a stem 23^a, threaded into a boss 23^b depending from the flange 24. The seat for this valve is provided by a sleeve or thimble 60^a, which may be threaded into the wall 13 of the valve casing. The valve disk may have a relatively sharp contacting edge or face as shown. This arrangement permits ready renewal of the parts most subject to wear.

In Figs. 7 and 8, I have shown another form of thermostat comprising a shell 40^a having flexible walls forming a chamber 43^a. This casing is mounted within a perforated shell or cover 52^a, and preferably the backing or supporting plate 46^a is concaved, conforming to the convexity of the walls of the casing 40^a. The backing plate is carried by the insulating plate 51^a, and may be held thereto by the screws 61 which hold the cover in place.

Engaging the opposite face of the casing 40^a is a movable plate 65 recessed at 66 to receive the end of an adjusting screw 47^a, and the latter may carry a dial 56^a, which may be set with reference to a pointer 57 carried by the casing 52^a. This structure may be attached to the insulating plate 51^a in a manner substantially similar to the structure illustrated in Fig. 2; such plate 51^a being in turn connected to an insulating plate 18^a carried by the bracket 17, which carries the valve. As in the structure shown in Fig. 2, the plates 18^a and 51^a are connected by a band 54^a perforated at 55^a.

The chamber 43^a of the casing 40^a is filled with liquid and operates in a manner precisely similar to the structure illustrated in Fig. 2, with a tube 37 affording communication between the chamber 43^a and the chamber of the valve; such tube 37 having the usual condensing portion 58^a disposed between the walls 18^a and 51^a.

In calibrating the structure shown in Figs. 1, 2, 3, et seq., to function properly, the screw plug closure 32 is removed, and the expansible chamber 43 of the thermostat, as well as the expansible chamber 22 of the valve body, is charged with a thermally affected liquid, such as alcohol, or other liq-

uid which vaporizes at less than steam temperature but above that of the normal temperature of the air. After such charging, the opening normally closed by the screw plug 32 is used as a vent to bleed the liquid from the chamber 22, chamber 27 and passage 35, in the top closure 16 for the valve body in order to properly calibrate the device and obtain the desired operating conditions for the temperatures involved. Such bleeding of the liquid provides a vapor space between the end of the tube 37 and the chamber 22. As may be well understood, the bleeding point may be disposed at some other part of the structure, but in any arrangement it should provide for an evacuation of the liquid from said chamber 22 so that under operating conditions such chamber is vapor-filled and never contains any of the liquid of the thermostatic chamber.

When completed and sealed tight by the closing of screw plug 32, and the steam valve 4 is properly connected in the steam supply pipe leading to the radiator, the action is as follows:

The screw 47 is revolved so that the mark or figure on the dial 56 representing, say 68° F. is opposite the pointer 57, then the body of thermal liquid is in the thermostat chamber 43, and there is no liquid in the chamber 22 of the expansible vessel 21, only vapor of the thermal liquid, at or below atmospheric pressure, together with the wax or other filler 39. The valve stem 23 is retracted, and the port 12 is open, permitting steam to pass from the chamber 14 of the valve 4. With steam flowing, the wax or other meltable filler within the chamber 22, (relatively solid at atmospheric temperature) becomes liquid, and the wall of the chamber 22 is then free to expand.

The heat of the steam expands the vapor in chamber 22, but not sufficiently to cause the chamber to expand materially. However, as the steam condenses in the radiator, the air of the room becomes warmer and rising above 68° F., at which point the thermostat is set to act, the liquid within said chamber 43 will expand, filling the coil 58 of the small tube 37, and the tubular passageway 35 in the cover 16, so that the heat in said cover 16, to which it is attached, vaporizes a portion of said liquid. If further increase in the volume of the thermal liquid in thermostat chamber 43 continues, such additional liquid will be forced toward the expansible chamber 22, and when the heat vaporizes it, it will increase the vapor pressure therein sufficient to expand the wall of said chamber 27; forcing valve 25 to its seat, closing the port 12, and cutting off the flow of steam.

Upon a decrease in temperature of the air at the thermostat chamber 43, the liquid contracts, and the vapor in chamber 22,

following the liquid, condenses in tube coil 58, returning to liquid form and relieving the vapor pressure in said chamber 22. Its resiliency, assisted by the fact that the pressure within is less than that without, causes the wall of the chamber 22 to retract and lift the valve 25 from its seat, thus opening the port 12.

This action will continue as long as the air at thermostat varies, and steam is present in the valve body 4. The vapor of the thermal liquid fills that part of chamber 22 not occupied by the fluid, and if this vapor space is small the action is quickened so that a slight change, a fraction of a degree at the thermostat, will expand the thermal liquid sufficiently to form vapor pressure in the chamber 22 that will close the valve 25.

20 When it is desired for any purpose, the volume of the wax or other material 39 in the chamber 22 may be reduced, then the vapor space is increased, requiring increased volume of vapor at the pressure required to close the valve and under this adjustment the change of air temperature at the thermostat must be greater to cause sufficient volume of the thermal fluid to be vaporized to produce the vapor pressure sufficient to 30 close the valve, thus the range of temperature through which the device will function is increased to 1°, 2°, or more, F., and the control of steam flow becomes more gradual.

To finally obtain the desired room temperature it is to be noted that with thermostat set at 68° F., a room temperature can be obtained at the breathing line of, say, 71° F., while if 68° F. is desired at the "breathing line," then the thermostat screw 40 47 should be rotated so that the line on dial coincident with pointer is 3 degrees less (71° - 68° = 3°) or 65° F. Then the controller is in adjustment for a room temperature of 68° F., at the "breathing line," 45 at which temperature it will close off the steam, and will operate continuously.

The structure shown in Figs. 7 and 8, may be calibrated in a manner substantially as described with reference to the other structure shown; and its operation is the same.

Because of conditions already explained, slight variations in "breathing line" temperature may occur, not due to any defects in the device but to the external atmospheric conditions described.

By the use of my invention, a means of controlling the temperature of rooms close to that required for comfort and health, simple and comparatively inexpensive, and 60 permanent in its function, is produced.

I claim:

1. In a heat controlling device; a thermostatic element, comprising an expansible chamber filled with an expansible and vaporizable fluid; a valve casing; an expans-

sible metallic chamber within said valve casing; a tube connecting said thermostatic element and metallic chamber whereby the fluid in the thermostatic element may communicate with said expansible metallic 70 chamber; and a filling substance within said metallic chamber adapted to solidify when the temperature of the steam is withdrawn.

2. In a heat controlling device, a thermostatic element, comprising an expansible 75 chamber filled with an expansible and vaporizable fluid; a valve casing having a valve port therein; an expansible metallic chamber within said valve casing; a valve piece carried by said chamber and adapted to automatically control said valve port to regulate the passage of steam therethrough; a tube connecting the thermostatic element and metallic chamber through which the fluid in the thermostatic element communicates with said metallic chamber; and a substance within said metallic chamber which solidifies at the temperature of the steam within said valve casing. 80

3. In a heat controlling device, a thermostatic element comprising an expansible chamber filled with an expansible and vaporizable fluid; a valve casing having a valve port therein; an expansible metallic chamber within said valve casing; a valve 90 piece carried by said chamber; a tube connecting said thermostatic element and metallic chamber through which the fluid from the thermostatic element communicates with said metallic chamber; and a filling substance within said chamber which solidifies at ordinary atmospheric temperature and liquefies at the temperature of steam and which by reason of a variation in the volume thereof, will change the range of 95 the temperature at which the valve piece closes the port in said valve casing to automatically control the passage of steam there-through. 100

4. In a heat controlling device, a thermostatic element comprising an expansible chamber filled with an expansible and vaporizable fluid; a valve casing having a valve port therein; a top closure for said valve casing; a tube affording communication between the thermostatic element and said top closure; an expansible metallic chamber in communication with said tube sealed to said closure and depending therefrom; a valve piece carried by said metallic chamber; and a filling substance within said chamber which solidifies at ordinary atmospheric temperature and liquefies at the temperature of steam, the amount of said filling substance determining the temperature at which the valve piece will close upon the port in 115 said valve casing to automatically control the passage of steam therethrough. 120

JAMES LOGAN FITTS.
